BUILDING UNIT

Wellington H. Spaulding, West Hempstead,
Long Island, N. Y.

Application July 5, 1940, Serial No. 344,141

12 Claims. (Cl. 72—37)

This invention relates to pre-formed building units for the construction of walls, buildings, or other structures, where such units are laid in a bonding material. Said units may be formed of any material suitable for the purpose, in any size or shape suitable to the material selected.

The general object of the invention is to provide a wall construction capable of resisting the penetration of moisture. Consequently the invention is especially adapted for use in exterior walls or surfaces exposed to the weather.

In my copending application, Ser. No. 266,880, filed April 8, 1939, issued August 13, 1940, as U. S. Letters Patent No. 2,211,521, whereof this application is a continuation-in-part (Ser. No. 266,880 is a continuation-in-part of Ser. No. 230,333, filed September 16, 1938), I disclosed inventions having the same general object.

As explained in said applications, a major disadvantage in walls constructed of conventional building units, such as walls formed with regulation brick or block and mortar, is that water or moisture is frequently able to enter through the vertical and horizontal joints between units. This is due principally to the poor bond or adhesion of the bonding material in the said joints or to shrinkage causing full depth unobstructed cracks in the joints, or to improperly filled joints due to the plain flat surfaces of ordinary bricks or blocks. The resultant penetration of moisture is increased by wind pressure.

In my aforesaid applications, I disclosed means for preventing this, consisting of building units formed with certain barriers, recesses, and dams, adapted to resist the passage of water and ensure a better bond of the bonding material in the joints. Certain of said features are employed in new and improved combinations with new features in my present invention.

A particular improvement of my present invention is the provision of one or more continuous barriers or projections on the sides, top and bottom of the building unit, so that when the units are laid in a wall construction, the barriers or projections create a continuous projection extending completely around the unit, projecting into the bonding material surrounding the unit. Such barriers are preferably located in corresponding vertical planes on all units, so that when laid in a wall construction, they will register with those on adjacent units. These continuous barriers or projections serve many unique and important purposes in this invention. The deformed faces created by the continuous barriers or projections increase and improve the

bonding area by forming tortuous surfaces between the unit and the bonding material. These continuous barriers or projections on the bonding surfaces of the unit tend to retain and cause a more uniform distribution of the bonding material within the jointing areas. In construction, they also create movement of the bonding material on the surface of the unit by compacting and displacement, thereby improving the adhesion of the bonding material to the unit. Also by confinement the bonding material is forced into every minute part. By this movement and compacting the adhesion of the bonding material is improved throughout the bonding area. Due to this displacement and the compacting action caused by the barriers or projections, the bonding material is materially reduced in thickness at each barrier or projection and the shrinkage of the bonding material is reduced in a like proportion, and since the essential portion of the mortar joints is isolated from atmospheric action, the shrinkage of the bonding material is reduced to a minimum. As these barriers or projections are continuous around each unit all of the aforesaid advantages are provided continuously around the jointing area of each unit, thereby creating a continuous improved mortar joint surrounding each unit that will resist the penetration of moisture.

A further advantage of my improved unit is that it is reversible, since the features on the top and bottom are identical, thereby providing two faces, either face being available for the exposed or finished surface, as with the common or ordinary brick or block.

These building units are designed to be laid in horizontal courses in any number of units in depth or bonded to any of the usual back-up materials, or to form a veneer on masonry, concrete or frame construction, or in one unit in depth or thickness, laid in mortar or any bonding material suitable for the purpose. These units may be laid in any bond desired, with exposed joints struck in any form desired. Walls constructed of these units have the same appearance as walls constructed of similar material using common or ordinary units. Building units of this invention when used in a wall or structure permit the usual or customary mechanical methods to be followed both in construction and workmanship.

Other objects and advantages of the invention will be understood from the drawing, and description thereof which follows. Whenever the term "building unit" is herein used, it is intended

to refer to all units of parallelepiped outline, irrespective of their specific dimensions, shape or form, material of which made, etc. For convenience the invention has been illustrated as applied to a building unit of the general dimensions of an ordinary brick, but it is to be understood that the invention is not limited to such bricks, and that the term "building unit" as used herein refers to all units to which the invention may be applied, irrespective of materials and dimensions.

In the drawing:

Fig. 1 is an isometric view of a unit embodying the invention;

Fig. 2 is an end elevation thereof;

Fig. 3 is a top plan view of units in the relative end-to-end position they would occupy in a wall construction, showing the vertical joints;

Figs. 4 and 5 are an elevation and section in plan, respectively, of a dam adapted to be placed in said vertical joints;

Fig. 6 is a transverse section through two units showing their relative positions in a wall structure;

Fig. 7 is a top plan view showing the invention embodied in a corner unit in a wall construction; and

Fig. 8 is a top plan view showing the invention embodied in a full header unit in a wall construction.

In Figs. 3, 6, 7 and 8, illustration of mortar or other bonding material has been omitted.

The unit illustrated in Figs. 1, 2, 3 and 6 employs two continuous barriers or projections 10 and 11, preferably centrally disposed on the unit and extending longitudinally on the top and bottom surfaces and vertically at the ends in a plane approximately parallel with the front and rear faces.

In Fig. 7, continuous barriers 10a and 11a are adapted to a corner unit. In Fig. 8 four continuous barriers 10b, 11b, 10c and 11c are shown on a full header unit. In all instances, more or fewer barriers may be employed, although the numbers thereof illustrated are at present preferred. Other locations of the barriers may also be employed so long as the object is fulfilled of providing a continuous barrier or barriers in the vertical and horizontal joints of units in a wall construction.

Between each pair of said continuous barriers on the top and bottom surfaces is located a V-shaped barrier 12 (top) and 13 (bottom). A modified V-shaped top barrier 12a is shown for the corner unit in Fig. 7, and 12b, 12c in Fig. 8. The purpose and functions of these barriers is described in my Ser. No. 266,880.

The registry of the foregoing barriers on units in a wall construction is illustrated in Figs. 3, 6, 7, and 8.

Between each pair of said continuous barriers on the vertical faces of the units are located semi-circular channels or grooves 14. In a wall construction these form a circular cavity best shown in Fig. 3, in which is located a dam 15, preferably tapered as shown in Figs. 4 and 5. The purpose and function of channels and dams of this type are described in my Ser. No. 266,880.

From the claims which follow, it will be understood that the above-described features or elements may be employed in various combinations without departing from the scope of the invention. In said claims where the "end," "ends," "end face" or "end faces" of a unit or units are

referred to, the terms will be understood to mean those portions of a unit adapted to form vertical joints with adjacent units, thereby rendering the claims applicable to embodiments required for corners and headers, such as shown in Figs. 7 and 8, as well as to the unit shown in Figs. 1, 2, 3 and 6.

What is claimed is:

1. A wall construction including in combination, a plurality of building units laid in a bonding material, each of said units having one or more pairs of spaced continuous barriers or projections extending over the horizontal and end faces of said units defining joints with opposite faces of adjacent units, channels or grooves each located between the barriers or projections constituting a pair, and positioned opposite each other, and dams located in the spaces formed by said opposed channels and embedded in the bonding material interposed between said end faces.

2. A building unit having a pair of continuous spaced barriers or projections on the top, bottom and end faces defining joints with adjacent units and adapted to be surrounded with a bonding material when laid in a wall construction, said continuous spaced barriers being located a distance from the forward and rearward faces of the unit, and having a V-shaped projection or barrier extending on the top and bottom faces, located between said pair of continuous spaced barriers, and having a channel or groove located between the said pair of continuous spaced barriers on the end faces of the unit.

3. A wall construction including in combination a plurality of building units laid in a bonding material, each of said units having a pair of continuous spaced barriers or projections on the top, bottom and end faces defining joints with adjacent units, said continuous spaced barriers being located a distance from the forward and rearward sides of the unit, and having a V-shaped projection or barrier extending on the top and bottom faces located between said pair of continuous spaced barriers, and having a channel or groove located between the said pair of continuous spaced barriers on the end faces of the unit, and dams located in the spaces formed by the opposing channels and barriers and embedded in said bonding material interposed between said end faces.

4. A wall construction resistant to the passage of moisture, including, in combination, a plurality of building units laid in a bonding material, each of said units having one or more continuous barriers or projections extending over the top, bottom, and end faces thereof where joints are defined with the faces of adjacent units, the barriers on adjacent units being in register and separated by bonding material filling the joints, said barriers thereby providing a continuous interval around each unit where the thickness of the bonding material is substantially reduced.

5. A wall construction resistant to the passage of moisture, including, in combination, a plurality of building units laid in a bonding material, each of said units having a pair of spaced continuous barriers or projections extending over the top, bottom and ends thereof where joints are defined with the faces of adjacent units, the barriers on adjacent units being in register and separated by bonding material filling the joints, said barriers thereby providing continuous intervals around each unit where the thickness of the bonding material is substantially reduced.

6. A wall construction according to claim 5, wherein end faces of each unit have a channel or groove between the barriers or projections thereon, and dams located in the space formed by said grooves in the vertical joints defined by adjacent units and embedded in the bonding material therein.
7. A wall construction resistant to the passage of moisture, including, in combination, a plurality of building units laid in a bonding material, each of said units having one or more continuous barriers extending over the top, bottom, and end faces thereof where joints are defined with faces of adjacent units, and bonding material separating said faces, said barriers projecting from said faces a distance less than one-half the thickness of said bonding material.
8. A wall construction according to claim 7, wherein the barriers on the faces defining joints with adjacent units are in register.
9. A wall construction according to claim 7, wherein the end faces of units defining joints are provided with vertical registering grooves, and dams embedded in bonding material in said grooves.
10. A building unit having one or more pairs of spaced continuous barriers or projections extending over its top, bottom and ends, and channels or grooves each located in one or more end faces of the unit between the barriers or projections constituting a pair, said barriers or projections being adapted to be surrounded with bonding material when the unit is laid in a wall construc-
tion; said unit having additional barriers or projections located between the continuous barriers or projections constituting a pair on the top and bottom faces of the unit respectively.
11. A wall construction including in combination, a plurality of building units laid in a bonding material, each of said units having one or more continuous barriers or projections, each of said barriers or projections extending over the faces of said units and surrounded with said bonding material where joints are defined with the faces of adjacent units; said units having channels or grooves in adjacent end faces of adjacent units and positioned opposite each other, and dams located in the spaces formed by said opposed channels and embedded in the bonding material interposed between said end faces.
12. A building unit having one or more pairs of spaced continuous barriers or projections extending over its top, bottom and ends, and channels or grooves each located in one or more end faces of the unit between the barriers or projections constituting a pair, said barriers or projections being adapted to be surrounded with bonding material when the unit is laid in a wall construction; said unit having additional projections or barriers on the top and bottom horizontal faces extending between and parallel to the spaced continuous barriers or projections constituting a pair, said pairs of continuous barriers located a distance from the forward and rearward faces of the unit.
